Patented Feb. 16, 1926.

1,573,478

UNITED STATES PATENT OFFICE.

CHARLES W. CARMAN, OF CHICAGO, ILLINOIS.

PHOTOGRAPHIC PRINT AND METHOD OF MAKING THE SAME.

No Drawing.

Application filed October 26, 1925. Serial No. 65,045.

To all whom it may concern:

Be it known that I, CHARLES W. CARMAN, a citizen of the United States, residing at Chicago, in the county of Cook and State 5 of Illinois, have invented new and useful Improvements in Photographic Prints and Methods of Making the Same, of which the following is a specification.

This invention relates to photographic 10 prints and the method of making the same, and is fully described in the following specification.

This process is particularly applicable to 15 pictures made on metal, notably silver or the like, which when treated according to my process imparts to the high lights of the picture a high luster, especially when viewed from certain angles.

This is a continuation in part of my 20 pending application Serial No. 17,436, filed March 21, 1925.

The process consists in taking a plate of silver, flattening it, eliminating all scratches or depressions by rubbing with fine emery 25 cloth, after which the face of the sheet is given a series of parallel scratches, preferably in a vertical direction, by rubbing it with emery cloth. The sheet is then cleaned in a solution of caustic soda after which it is 30 washed and ready to receive the print. In the case of silver, oxidation takes place so readily that the print should be applied thereon as soon as possible after the prepared plate is cleaned and washed.

35 While there are various ways in which the print may be applied to the prepared silver surface, I prefer to make this print upon a photographic transfer paper which consists of paper having a coating of gelatin or the like carrying a light-sensitive pigment. An exposure is then made on this sensitized paper, preferably by contact with a continuous tone negative in a well known manner.

45 This print is then placed in clean water in contact with the scratched prepared silver surface and the print pressed firmly down thereon, the scratches of the prepared surface preferably lying vertical with respect to the picture.

50 The plate with the paper print thereon is then removed from the water and squeegeed into contact with the metal plate. It is then dried from 10 to 20 minutes to cause it 55 to adhere more firmly to the metal surface, after which it is soaked in hot water at a

temperature of 100 to 110° F. and until the paper will readily peel off leaving the sensitized gelatin on the surface of the metal plate. The picture is then developed by 60 washing out a portion of the gelatin which has not been acted upon by the light, thereby leaving upon the surface of the metal plate the picture in varying degrees of relief. The picture is then fixed in a solution of alum, washed and dried in a well known manner, after which it is treated with a coat of transparent metal lacquer to 65 preserve it.

By scratching this surface as I have done, 70 a series of bright parallel lines or scratches are produced in the surface of the metal which readily catch and reflect light so that the sharpness of the high lights is greatly magnified in contrast to the darker portions 75 of the picture through which relatively little of this reflected light can pass. The result is that this method greatly increases the brilliance and pleasing appearance of any photographic print made in this way. 80

It will be understood that while a transfer process is here described, it is illustrative only, and that other transfer processes may readily be used or, if desired, a sensitized gelatin coating may be placed directly upon 85 the surface of the metal plate prepared as has heretofore been described, and the exposure and developing may be made in any of the well known ways directly upon this coated plate, after which it may be developed, washed and fixed in any well known 90 manner.

Metals other than silver may be used for 95 this purpose. For example, the prepared surface of the plate may be gold plated and polished, and the picture then deposited as has been described upon this gold plated surface.

While I have described but a few of the 100 embodiments of my invention, it is to be understood that it is capable of many modifications. Changes therefore in the method and arrangement may be made without departing from the spirit and scope of my invention as covered by the appended claims. 105

I claim:

1. The method of making photographic prints on metal consisting of forming in the face of the metal a series of parallel scratches, and applying thereon a continuous tone photographic print. 110

2. The method of making photographic

prints on metal consisting of forming in the face of the metal a series of parallel scratches, and applying thereon a continuous tone photographic print, the deep shadows of which are in strong contrast to the high-lights.

3. In a photographic print, a metal base having a series of parallel scratches in its face, and a continuous tone photographic print on said surface.

4. In a photographic print, a metal base having a series of parallel scratches in its face, and a continuous tone photographic print on said surface, the deep shadows of

which are in strong contrast to the high-lights.

5. In a photographic print, a metal base having a series of parallel scratches in its face, and a continuous tone carbon print on said surface.

6. In a photographic print, a silver base having a series of parallel scratches in its face, and a continuous tone photographic print on said surface.

In testimony whereof I have hereunto set my hand this 15th day of October, 1925.

CHARLES W. CARMAN.
